UNITED STATES PATENT OFFICE.

GEORGE WEST BYRON, OF WASHINGTON, DISTRICT OF COLUMBIA.

AIR-SHIP.

No. 839,548.

Specification of Letters Patent.

Patented Dec. 25, 1906.

Application filed February 11, 1905. Serial No. 245,276.

To all whom it may concern:

Be it known that I, GEORGE WEST BYRON, of Washington, in the District of Columbia, have invented certain new and useful Improvements in Air-Ships; and I do hereby declare the following to be a full, clear, and exact description of the invention, such as will enable others skilled in the art to which it appertains to make and use the same.

10 This invention relates to certain new and useful improvements in air-ships.

The invention has for its object the production of an air-ship which will form minimum resistance to the wind-currents, whereby the control of the same is rendered possible.

A further object is to so locate the cabin or other place for the accommodation of passengers or freight as to afford the least possible resistance to the buoyancy of the air-ship.

20 A further object is to so position said cabin as to protect the same from the wind and other air currents, whereby the drag of the air-currents upon depending cages is obviated.

A further object is to provide means for 25 assisting the air-ship in its initial movement incident to elevation and flight.

A further object is to produce an air-ship which combines the principles of the dirigible balloon and the aeroplane.

30 To these ends the invention will be herein-after fully set forth, and particularly pointed out in the claims.

In the accompanying drawings, Figure 1 is a side elevation illustrating my invention. 35 Fig. 2 is a plan view with the upper supplemental gas-bag removed. Fig. 3 is a cross-section on the line 3 3, Fig. 1.

Referring to the drawings, 10 designates a frame formed of a plurality of metal bars, to 40 which are secured a plurality of gas-bags 11 12, said gas-bags being arranged around said frame so as to completely inclose the same to form a cabin or space for the accommodation of passengers or freight and also for any suitable motor. These gas-bags may be of any 45 preferred shape in plan, the bags 11 being shown as triangular in plan to form the bow of the ship, the remaining gas-bags being rectangular in plan. The gas-bags 11 are

50 made of substantial wedge shape, being provided with a narrow exterior edge the thickness of the bag, increasing to a maximum at its inner edge. It will be noted in this connection that the wedge formation is secured by arranging the bottom wall of each gas-bag on an approximately horizontal plane,

the top wall sloping upward from the narrow outer edge to the point of maximum thickness, at which point the top and bottom walls are united by a suitable vertical wall, as shown. 60 If desired, a passage-way 13 may be arranged between the bags 11 and a similar passage-way 14 between the rearmost bags 14. As shown, the bars of frame 10 correspond in length to the dimensions of the several gas-bags, the latter being secured to the horizontal bars 15 and the vertical bars 16, the latter forming the framework for the cabin. Said frame is provided with a centrally-located depending ballast-frame 17, which serves to 65 aid in balancing the ship, a suitable stairway 18 leading from the cabin to the bottom rail of said ballast-frame, whereby passengers may ascend or descend. At the forward corners of this ballast-frame are pivotally secured bars or legs 19, similar shorter bars or legs being pivoted to the rear corners of the machine, said bars or legs being designed to support the air-ship when resting upon the ground. I also provide a propeller 21 at the 70 forward end of the gas-bags for the purpose of assisting in elevating or depressing the bow of the ship. Similar propellers 22 are also located on each side for guiding the ship laterally, and propellers 23 are located at the 75 rear for the purpose of driving the ship forward, said propellers being operated by any suitable motor.

If desired, when the load to be transported is unusually heavy I employ a supplemental 90 gas-bag 24, secured to upright bars 25 of the frame 10 and extending over the bags 11 12, said gas-bag 24 being of any suitable dimensions and of approximately wedge shape—i. e., very narrow at the edges, with the thickest point at the center. The gas-bag 24 is constructed on similar principles to the gas-bags 11 12, i. e., it is so supported that the bottom wall thereof is on an approximately horizontal plane, while the wedge formation is 100 obtained by sloping the top wall upward from the outer edge of the gas-bag. I may also employ smaller supplemental gas-bags 26, arranged just over the cabin.

In practice by forming the bottom wall of 105 the gas-bag on an approximately horizontal plane my improved air-ship in its flight possesses many of the characteristics of the aeroplane, the horizontal surface thus secured tending to add to the buoyancy of the ship. 110 When prepared for a flight, the ship rests upon the ground, as illustrated in Fig. 1.

When the propellers 23 are put in motion, the ship is forced forward, and this forward movement has the effect of straightening the legs or bars 19 to a perpendicular, thus elevating the forward end or bow, whereupon the full benefits of the aeroplane qualities are secured. The elevation of the forward end is assisted by propeller 21. When the additional gas-bag 24 is employed, the dirigible bodies having horizontal under faces combine all of the characteristics of a kite constructed on the aeroplane principle, thus securing an increase of buoyancy far in excess of that secured merely by the increased volume of gas contained in the additional gas-bag.

It will be particularly noted that by making the gas-bags of approximately wedge shape the same present but a minimum resistance to the wind or other air-currents, and the ship is therefore more readily controlled in its flight. A further advantage is obtained by surrounding the cabin or space for the accommodation of passengers or freight by the gas-bags, so that the only resistance to the air-currents is that afforded by the gas-bags themselves. At the same time the same does not interfere with the buoyancy of the ship. The latter is also balanced in its flight by the depending ballast-frame, which being formed of metallic bars which are widely separated, affords practically no resistance to the air. It will also be observed that I have provided means for assisting the ship in its initial elevating movement and that the same is readily propelled. By employing a plurality of gas-bags in lieu of one great bag I render my improved airship practically immune from sudden falling by reason of the collapse of the supporting gas-bag. By virtue of my construction one or more of the gas-bags may collapse, and yet the others would still retain sufficient buoyancy to support the ship or at least permit the same to slowly descend without injury to the passengers or cargo.

I claim as my invention—

1. An air-ship comprising a plurality of wedge-shaped gas-bags, the bottom walls of which are flat, said gas-bags being arranged in a group with the bottom walls on a horizontal plane and presenting the thin or narrow edge to the outside of the group in all directions.

2. An air-ship comprising a plurality of wedge-shaped gas-bags the bottom walls of which are flat, said gas-bags being arranged in a group with the bottom walls on a horizontal plane and presenting the thin or narrow edges to the outside of the group in all directions, the thicker portions of the gas-bags being arranged to form the walls of an enclosed space.

3. An air-ship comprising a plurality of wedge-shaped gas-bags the bottom walls of which are flat, said gas-bags being arranged

in a group with the bottom walls on a horizontal plane and presenting the thin or narrow edges to the outside of the group in all directions, the thicker portions of the gas-bags being arranged to form the walls of an enclosed space having longitudinal passageways leading therefrom.

4. An air-ship comprising a frame, a plurality of wedge-shaped gas-bags secured in a group around said frame with the bottom walls on a horizontal plane and presenting the thin or narrow edges to the outside in all directions, and a ballast-frame depending from the first-mentioned frame.

5. An air-ship comprising a frame, a plurality of wedge-shaped gas-bags connected thereto, said gas-bags being arranged in a group with the bottom walls on a horizontal plane and presenting the thin or narrow edges to the outside in all directions, a propeller for imparting an upward tendency to the forward end of the ship, and means for imparting an initial upward tilt to the forward end of the ship at the commencement of its flight.

6. An air-ship comprising a frame, a plurality of wedge-shaped gas-bags connected thereto, said gas-bags being arranged in a group with the bottom walls on a horizontal plane and presenting the thin or narrow edges to the outside in all directions, a propeller for imparting an upward tendency to the forward end of the ship, and pivoted legs or members for imparting an initial upward tilt to the forward end of the ship at the commencement of its flight.

7. An air-ship comprising a frame, a plurality of wedge-shaped gas-bags connected thereto, said gas-bags being arranged in a group with the bottom walls on a horizontal plane and presenting the thin or narrow edges to the outside in all directions, a propeller for imparting an upward tendency to the forward end of the ship, and pivoted legs arranged adjacent each end of the ship, the legs adjacent the forward end being longer than those at the rear, whereby an initial upward tilt is given to the forward end of the ship at the commencement of its flight.

8. An air-ship comprising a frame, a plurality of wedge-shaped gas-bags arranged in a group around said frame, with the thin edges presented to the outside in all directions, a propeller for imparting an upward tendency to the forward end of the ship, and means for imparting an initial upward tilt to the forward end of the ship at the commencement of its flight.

9. An air-ship comprising a frame, a plurality of wedge-shaped gas-bags arranged in a group around said frame, with the thin edges presented to the outside in all directions, a supplemental wedge-shaped gas-bag secured to said frame above the first-mentioned gas-bags, a propeller for imparting an

upward tendency to the ship, and means for imparting an initial upward tilt to the ship at the commencement of its flight.

10. An air-ship comprising a frame, a plurality of gas-bags of wedge shape arranged in a group around said frame, said bags being arranged to present their thin edges to the outside in all directions and with their bottom walls arranged on a horizontal plane, a propeller for imparting an upward tendency to the forward end of the ship, a depending

ballast-frame, and pivoted legs carried by said ballast-frame for imparting an initial upward tilt to the forward end of the ship at the commencement of its flight.

In testimony whereof I have signed this specification in the presence of two subscribing witnesses.

GEORGE. WEST BYRON.
